CLAIM

We claim the ornamental design for a safety station, as shown and described.

DESCRIPTION

FIG. 1 is a perspective view of an embodiment of a safety station of the claimed design;

FIG. 2 is a front view of the claimed design shown in FIG. 1;

FIG. 3 is a back view of the claimed design shown in FIG. 1;

FIG. 4 is a left side view of the claimed design shown in FIG. 1;

FIG. 5 is a right side view of the claimed design shown in FIG. 1;

FIG. 6 is a top view of the claimed design shown in FIG. 1; and,

FIG. 7 is a bottom view of the claimed design shown in FIG. 1.

The ornamental design that is claimed is shown in the drawings as solid lines and surfaces having surface shading. In the drawings, the broken lines are for the purpose of illustrating portions of the safety station which form no part of the claimed design.
